US0D1069641S

(12) United States Design Patent (10) Patent No.: US D1,069,641 S
(45) Date of Patent:  Apr. 8, 2025

(54) PLANTER

(71) Applicant: Vitra AG, Birsfelden (CH)

(72) Inventor: Goupil Thélonious, Saint-Pierre-en Port (FR)

(73) Assignee: Vitra AG, Birsfelden (CH)

() Term: 15 Years

(21) Appl. No.: 29/889,347

(22) Filed: Apr. 11, 2023

(30) Foreign Application Priority Data

Oct. 12, 2022 (WO) 123667

(51) LOC (15) Cl. 11-02

(52) U.S. Cl.

USPC D11/152
